UNITED STATES PATENT OFFICE.

RAYMOND SECKER, OF WHEATON, ILLINOIS.

DESIGN FOR A DIRECTION SIGNAL AND TAIL LIGHT FOR MOTOR VEHICLES.

Application filed April 25, 1921. Serial No. 464,463. Term of patent 3½ years.

To all whom it may concern:

Be it known that I, RAYMOND SECKER, a citizen of the United States, residing at Wheaton, county of Du Page, State of Illinois, have invented a new, original, and ornamental Design for a Direction Signal and Tail Light for Motor Vehicles, of which the following is a specification, reference being had to the accompanying drawing, forming part thereof.

The figure is a plan view of a direction signal and tail light for motor vehicles, showing my new design.

I claim:

The ornamental design for a direction signal and tail light for motor vehicles, as shown.

RAYMOND SECKER.
